FILTER, STRAINER, AND THE LIKE

Frank Oscar Levi Chorlton, Bury, England

Application October 12, 1935, Serial No. 44,794

In Great Britain October 27, 1934

6 Claims. (Cl. 210—169)

This invention relates to filters or strainers, and more particularly to filters or strainers for separating very fine solid particles from oil.

I have illustrated my invention in the accompanying drawing, in which:—

Figs. 1 and 2 show a cage construction suitable for use in that type of filter in which the cage on which the wire is wound is fixed in locating seatings in the filter casing so that the filtering medium is interposed between the inlet and the outlet;

Fig. 1 being a sectional elevation on the line I—I of Fig. 2; and

Fig. 2 a plan, the left-hand half showing the casing and cover in medial section, and the right-hand half showing the casing and cover in medial section and also showing the cage in section on the line II—II of Fig. 1.

Fig. 3 is an elevation of a rotatable filtering unit showing a method of cleaning.

Figs. 4 to 11 illustrate cross-sections of wire which may be employed in carrying out the invention.

Fig. 12 illustrates to a considerable enlarged scale a fragmentary section on the plane XII—XII of Fig. 1 as shown to a smaller scale at x of Fig. 2, and

Figs. 13 and 14 are views similar to Fig. 12 and show grooves modified to suit wires of semi-circular and trapezoidal shape.

Referring first to Figs. 1 and 2:—

A is a cage or former comprising a cylindrical portion a₁ having externally projecting longitudinally disposed ribs a₂, forming water-ways a₃; at opposite ends the ribs a₂ are connected by flanges a₄ which fit with suitable jointing, in seatings b₁ and b₂ of the filter casing B. In the outer faces a₆ of the ribs a₂ which are of cylindrical configuration, grooves are cut which form interrupted portions of a helical groove running from end to end of the cage, the pitch of which is slightly greater than the maximum transverse dimensions of the wire employed; if a wire of triangular cross-section (as shown in Fig. 4) is employed, a V-shaped groove (as shown in Fig. 12) would be cut, the depth of the groove being less than the distance from the apex of the triangle (Fig. 4) to the base thereof; a portion of the wire winding is shown at C; the ends of the wire are suitably secured and the cage is retained in any suitable manner in its seatings b₁ and b₂ across the water-way of the filter, the arrangement being such that liquid can pass from the inlet part b₃ of the filter to the outlet part b₅ through the filtering medium only; in Figs.

1 and 2 the flow of the water to be filtered is inwardly through the helical interstices between the convolutions of the wire, the water passing to the several longitudinal water-ways a₃ and thence either directly through the openings a₅ to 5 the main outlet b₅, or to the recess b₄ and thence to the outlet b₅ through the interior of the cage.

Referring to Fig. 3:—

The arrangement is similar to that already described except that the cage or former A' is rotatably mounted in the casing B'; the former A' is provided with interior teeth a₂₀ with which a wheel G engages; the wheel G is mounted on a spindle g₁ mounted in the casing A, and is adapted to be rotated by any suitable means, for example by an external handle on the spindle g₁ or by power, and a brush H is mounted on a spindle h₁ in the casing in contact with the filtering medium, whereby when the cage A' is rotated the filtering medium is cleansed from dirt or other matter adhering to the outside.

The filtering medium formed of wires of sections shown in Figs. 4 to 11 may be employed, the shape of the helical groove being modified as shown for example in Figs. 12 and 13.

Of the sections of wire given by way of example in Figs. 4 to 11, the wires shown in Figs. 4, 5, 7, 8 and 11 are suitable for those cases in which the grooves in the ribs on which the wires are wound are adapted to take the apex or narrowest part c₁ of the section, as in Figs. 12, 13 and 14.

In the cases of wires of the sections shown in Figs. 4, 5 and 8 the surface presented to the flow of liquid to be filtered is practically the plain cylindrical surface formed by the aligning faces c₂ of the base of the section; in Figs. 7 and 11 the surfaces on each side of the entrance to the helical passage-way form a re-entrant angle which is found to be of advantage in some cases.

The sections shown in Figs. 6, 9 and 10 are suitable for use when the grooves in the ribs are adapted to take the shaped base part c₄ of the section, for example, in Figs. 6 and 9 the wire could be wound in helical grooves of circular cross-section after the manner shown in Fig. 13, the radius of curvature being considerably increased to agree with that of c₄ of Figs. 6 and 9, and the depth of groove considerably diminished; similarly the wire of Fig. 10 could be wound in helical grooves of triangular cross-section as in Fig. 12, the angle between the sides of the grooves being an obtuse angle as at c₄ Fig. 10 and much shallower than that shown in Fig. 12.

5 The bases $c4$ (Figs. 6, 9 and 10) are in the construction last described on the entrance side to the helical groove, the flow in this case being outwardly through the wire-wound filtering medium; the radius of curvature of the sides of the base $c4$ of Figs. 6 and 9 is therefore made comparatively great, and the angle between the two sides of the base $c4$ in Fig. 10 is made very obtuse, in order to prevent any wedging action taking place which would tend to clog the entrance to the helical passage-ways.

10 The configuration of the unit is above referred to as approximately cylindrical but obviously the wire-wound helix is not truly cylindrical but polygonal, and where desired the body part $a1$ of the cage A may be made polygonal.

15 Having now fully described my invention, what I claim and desire to secure by Letters Patent is:—

20 1. In filtering apparatus in combination;—a filter casing having inlet and outlet openings; a cage located within the casing and having peripherally situated, circumferentially spaced, longitudinally disposed upstanding members constituting 25 a polygonal former to support a filtering element comprising a wire helix wound thereon with a space between successive convolutions; jointing means on the casing and on the cage which when 30 jointed connect the enclosed space outside the helix to one of the said casing openings and the enclosed space within the helix to the other said opening; and a filtering element consisting of a wire helix wound on said cage members with a space between its successive convolutions, the 35 normal transverse cross-section of the wire of which the helix is wound being a segment of a circle, the helix being wound with a part of the circular periphery of the wire on and supported by the longitudinal members of the former, and 40 with the side of the wire which in transverse section is a straight line disposed in a surface of revolution, the generatrix of which is a line, and the axis of which is the axis of the helix, the pitch of the helix being slightly greater than the 45 width of the said side.

2. In filtering apparatus in combination;—a cage comprising a hollow cylindrical portion with end flanges, the outer portion of the cylinder having a series of circumferentially spaced ridges 50 forming a series of shallow troughs bounded by the flanges and the ridges, passage-ways being provided through the flanges, one at each end

5 of each trough; a cylindrical casing open at one end to admit the cage and having an opening through the opposite end and an opening through the side of the casing, one of said openings forming the inlet and the other the outlet for the fluid to be filtered; a seating in the said casing located between the two said openings to make joint with the inner flange of the cage when the latter is inserted in the casing; a seating at the open end of the casing to make joint with the other flange of the inserted cage; and a cover 10 to close the open end of the casing, the inner face of said cover being some distance axially away from the adjacent flange of the cage; and a filtering medium consisting of a wire helix 15 wound on said cage ridges with a space between its successive convolutions, the normal transverse cross-section of the wire of which the helix is wound being a figure having one side which is approximately a straight line of length greater 20 than any other transverse dimension of the figure parallel to said line, the two sides of the figure adjacent the said straight line side converging in a direction away from the said straight line, the helix being wound with the side of the wire corresponding with the said straight line substantially forming a plain cylindrical surface. 25

3. A filter constructed in accordance with claim 2, and in which the inlet for the flow of fluid to be filtered is the side opening of the casing, in which the wire forming the helix is of triangular cross-section wound on the cage so that the apex is supported by the ridges of the cage and the side of the wire opposite the apex 35 is wound to form a plain cylindrical surface intersected by a helical slot.

4. A filter constructed in accordance with claim 2, and in which the inlet for the flow of fluid to be filtered is at the end of the casing 40 in which the wire forming the helix is of triangular cross-section wound on the cage so that one side of the wire is supported by the ridges, the helix having a plain cylindrical interior traversed by a helical slot. 45

5. A filter constructed in accordance with claim 2, in which the wire forming the filtering medium is of trapezoidal cross-section.

6. A filter constructed in accordance with claim 2, in which the wire forming the filtering 50 medium is of semi-circular cross-section.

FRANK O. L. CHORLTON.
